UNITED STATES PATENT OFFICE.

ALBERT V. DOUGLAS, OF PUEBLO, COLORADO.

MEANS FOR SHAPING AND TEMPERING LEAF SPRINGS.

Application filed May 9, 1921. Serial No. 468,189.

To all whom it may concern:

Be it known that I, ALBERT V. DOUGLAS, a citizen of the United States, and a resident of Pueblo, in the county of Pueblo and 5 State of Colorado, have invented a new and useful Improvement in Means for Shaping and Tempering Leaf Springs, of which the following is a full, clear, and exact description.

10 My invention relates to improvements in means for and methods of shaping and tempering leaf springs, and it consists in the combinations, constructions and arrangements herein described and claimed:

15 An object of my invention is to provide a simple, inexpensive, and effective means for shaping leaves of leaf springs as desired and for maintaining the leaves in adjusted relative positions while immersed in a tempering fluid.

20 A further object of my invention is to provide a device of the character described in which a spring leaf may be shaped as desired and submerged in a tempering fluid 25 while being maintained in shaped form.

A further object of my invention is to provide a device of the character described that is adapted for use in shaping and tempering spring leaves of various sizes.

30 A further object of my invention is to provide a method of forming leaf springs in which each leaf spring is subjected to a shaping strain and simultaneously immersed in a tempering fluid.

35 A further object of my invention is to provide a method of forming leaf springs in which a main spring leaf is first shaped and tempered and the superposed leaves are then successively shaped with respect to the 40 contiguous leaf and subsequently tempered.

Other objects and advantages will appear in the following specification, and the novel features of the invention will be particularly pointed out in the appended claims.

45 My invention is illustrated in the accompanying drawings, forming part of this application, in which—

Fig. 1 is a front elevation of the device,
Fig. 2 is an end view of the same,

50 Fig. 3 is a section along the line 3—3 of Fig. 1,

Figures 4 and 5 are details of fragmentary portions of the device.

In carrying out my invention, I provide a 55 tank 1 open at its upper end and adapted to hold a tempering fluid. The walls of the

tank are reenforced at the corners by vertical members 2 and certain of these members are provided with extensions 3 converging at their upper ends as shown or the extensions 3 may be separate members secured to the tank 1 in any suitable and well known manner. The extensions 3 are secured at their upper ends to a vertical support 4 that preferably has the form of an I-beam secured to the rear wall of the tank. The support 4 is bent forwardly adjacent to its upper end and a vertical guide member 5 is secured thereto at its upper end by bolts 6 like fastening means. The guide member 5 is stayed at its lower end by a bar 7 secured thereto and to the I-beam 4. A work supporting frame 8 is horizontally disposed and is guided by relatively arranged vertical guiding and retaining members 9 secured to the inner walls of the tank 1 as shown. In the form of the device now preferred by me, the work engaging frame is rectangular in form and has the section of an angle iron arranged with one leg thereof horizontally disposed to provide a flat upper surface. The work engaging frame is connected by tie rods 10 with an upper horizontally disposed rectangular frame 11 which carries a guide frame consisting of spaced apart pairs 85 of vertical bars 12—12 and 13—13 and upper and lower pairs of horizontally disposed bars 14—14 and 15—15, respectively, secured at their ends to the vertical bars 12—12 and 13—13, the horizontal bars 90 of each pair being spaced apart intermediately to provide vertically alined guideways for the guide member 5. The upper rectangular frame 11 is stayed by tie rods 16 connecting the latter with the vertical 95 bars 12—12 and 13—13 adjacent to the upper ends of the latter.

A link 17 is pivoted at its lower end to one of the horizontal guide frame members 15 and at its upper end to lever 18 that is 100 fulcrumed at 19 on the web of the support 4, the adjacent flange of the latter being cut away at 20 to permit movement of the lever. A spring 21 secured at its upper end to the support 4 and at its lower end to the lever 18 adjacent to or at the point of connection of the latter with the link 17 tends to maintain the lever 18 in the position shown best in Fig. 2, whereby the work engaging frame is normally maintained above the level of 110 a tempering fluid in the tank 1.

Superposed on the work supporting frame

- 8 is a transverse work engaging member 22 disposed substantially midway between the ends of the work supporting frame and rigidly secured to the side members thereof.
- 5 A pair of spaced apart upstanding brackets or lugs 24—24 are secured to one of the side members of the work supporting frame at opposite sides of the work engaging member 22 by means of screws 23 or the like,
- 10 and a screw 25 threaded through a carrying plate 26 is adjustably maintained parallel with the work engaging member 22 and in a higher plane as will now be described. The carrying plate 26 has openings therethrough
- 15 registering respectively with vertically extending slots 28—28 through the lugs 24—24 and the screw 25 is maintained in adjusted position relative to the member 22 by means of clamping members 29—29, such as bolts
- 20 projected through the openings in the plate 26 and the slots 28—28. The screw 25 is formed with a crank 30 integral therewith to permit convenient operation of the former.
- 25 A pair of identical end transverse work engaging members 31—31 are provided, each consisting of a substantially U-shaped bar having a relatively long horizontally disposed lower arm 32 provided with pins
- 30 33—33 at each end thereof, and a horizontally disposed upper arm 34 that terminates short of the end of the lower arm 32. The pins 33—33 are adapted to enter spaced apart openings 35—35 through the side
- 35 members of the work supporting frame 8, whereby the end work engaging members may be positioned at various distances from the middle stationary work engaging member. The arms 32 and 34, respectively, of
- 40 each end member 31 are formed with aligned openings 36 and 37 therethrough and a retaining pin 38 may be projected through selected aligned openings for a purpose which will be hereinafter set forth.
- 45 A plurality of intermediate work engaging members or rests 39 are identical with each other in essential respects and are each formed with pins 40—40 at the ends thereof in position to enter selected openings 35—35,
- 50 whereby the intermediate work engaging members may be positioned as desired with respect to the movable end members 31—31 and the fixed intermediate member 22.
- From the foregoing description of the
- 55 various parts of the device, the operation thereof may be readily understood. The device is designed primarily for use in shaping and tempering the leaves of leaf springs such as are usually installed in automobiles
- 60 and other vehicles. A main spring leaf 41 is placed upon the work engaging members with the ends thereof disposed between the arms of the end members 31—31 and engaging the retaining pins 38—38. The crank 30
- 65 is manipulated to operate the tension-ad-

justing screw 25 so that the leaf 41 will be bowed intermediately to shape the same as desired.

It will be understood that the leaf 41 is in a heated condition at this time. The lever 18 is then moved downwardly against the tension of the spring 21, thereby moving the work supporting frame downwardly in the tank 1 until the leaf 41 is submerged in a tempering fluid 42, such as oil. When the leaf has been tempered, the lever 18 is released and the work supporting frame is moved upwardly by the action of the spring 21. The main leaf is maintained in the position shown after the tempering thereof and the leaves to be superposed thereon which prior to tempering are normally straight are successively heated and clamped tightly to the cold proximate leaf by clip tongs 43 and immersed in the tempering fluid by operation of the lever 18 in the manner hereinbefore described. Obviously, a suitably tempered and shaped main leaf may be adjusted on the work supporting frame and auxiliary leaves then shaped and tempered for connection therewith, as when it is desired to repair leaf springs in which the main leaf is intact. The device is adapted for use in shaping and tempering leaves of various sizes and provides a relatively simple and effective means for performing the functions for which designed.

I claim:

1. The combination with a vessel partially filled with a tempering fluid of a work supporting frame provided with adjustable means for engaging spring bars of various sizes to shape the latter as desired and for maintaining them in shaped form, a support carried by the vessel and extending above the vessel, a vertical guide bar depending from the support, a guide frame slidable vertically on the guide bar, a lever fulcrumed on the support and having a connection with the guide frame, means connecting the guide frame and the work supporting frame, and spring means connecting the lever and the support, whereby the work supporting frame is normally supported above the level of the tempering fluid in the vessel and is movable vertically into the vessel against the tension of the spring means.

2. In a device of the character described, a substantially rectangular work supporting frame, transverse work engaging members detachably connected to the frame at spaced distances from the ends thereof, each of said members comprising a U-shaped bar having the arms thereof horizontally disposed and provided with vertically aligned openings and with a retaining pin projected through the aligned openings, and an intermediate transverse work engaging member fixedly connected to the frame and pro-

vided with a screw arranged to contact a bar disposed upon said work supporting frame, whereby a stress may be imposed upon said bar to occasion the bending of the latter intermediately and the clamping

5 of the bar between the end of the screw and the retaining pins of the end work engaging members.

3. In a device of the character described, 10 a substantially rectangular work supporting frame, transverse work engaging members detachably connected to the frame at spaced distances from the ends thereof, each of said members comprising a U-shaped bar 15 having the arms thereof horizontally disposed and provided with vertically aligned openings and with a retaining pin projected through the aligned openings, an intermediate transverse work engaging member fixedly 20 connected to the frame and provided with a screw arranged to contact a bar disposed upon said work supporting frame, whereby a stress may be imposed upon said bar to occasion the bending of the latter intermediately and the clamping of the bar be-

25 tween the end of the screw and the retaining pins of the end work engaging members, and manually operated means for lowering and raising said work supporting frame at will.

4. In a device of the character described, 30 a work supporting frame, transverse work engaging members detachably connected to the frame at spaced distances from the ends thereof, said members arranged to engage 35 opposite ends of a bar placed upon said work supporting frame, an intermediate transverse work engaging member fixedly connected to said frame and provided with a screw arranged to contact said bar, whereby a stress may be imposed upon said bar to occasion the bending of the latter intermediately and the clamping of said bar between the end of said screw and the points of engagement of said transverse engaging 40 members and said bar, and means permitting said work frame to be lowered into a tempering liquid and raised therefrom at will.

45 ALBERT V. DOUGLAS.
